FIG. 5

FIG. 11

FIG. 6

FIG. 10

FIG. 7

FIG. 8

FIG. 9

FIGURE 1 is a view in perspective of one embodiment of lighting fixture, showing my new design;

FIGURE 2 is a view in side elevation of the lighting fixture shown in FIGURE 1;

FIGURE 3 is a bottom plan view of the lighting fixture shown in FIGURE 1;

FIG. 4 is an enlarged fragmentary sectional view taken along line 4-4 of FIG. 2;

FIGURE 5 is a top plan view of the lighting fixture shown in FIGURE 1;

FIGURE 6 is a view in perspective of another embodiment of lighting fixture of this invention;

FIGURE 7 is a view in side elevation of the lighting fixture shown in FIGURE 6;

FIGURE 8 is a bottom plan view of the lighting fixture shown in FIGURE 6;

FIGURE 9 is a view in end elevation of the lighting fixture shown in FIGURE 6;

FIGURE 10 is an enlarged fragmentary sectional view taken along line 10-10 of FIG. 6;

FIGURE 11 is a top plan view of the lighting fixture shown in FIGURE 6.

The dominant features of my design reside in the portions shown in full lines.

The texture partially shown on the bottom and side surfaces of the fixture indicates conventional lens faceting and is understood to cover said surface areas.

I claim:

The ornamental design for a lighting fixture, as shown and described.
